UNITED STATES PATENT OFFICE.

MICHAEL MOLNAR, OF CLEVELAND, OHIO.

BEAN-SHELLING DEVICE.

Application filed October 5, 1920. Serial No. 414,841.

To all whom it may concern:

Be it known that I, MICHAEL MOLNAR, citizen of the United States, residing at Cleveland, in the county of Cuyahoga and State 5 of Ohio, have invented new and useful Improvements in Bean-Shelling Devices, of which the following is a specification.

This invention relates to a bean shelling device, or thresher, and the object is to provide a device by means of which the beans or peas to be shelled may be effectively removed from the pods, and discharged to a sifting screen, and discharged thence to a bag or other receptacle.

15 A further object is to provide in a device of the type indicated, a rotary device having teeth on the surface thereof, or on both surfaces, for cooperation with teeth formed on a stationary element or elements adjacent to 20 which the rotary element operates.

A still further object is to provide means for yieldingly mounting the rotary element, permitting the latter to be used in shelling various sizes of beans, without damaging 25 the latter by abrasion.

With the foregoing and other objects in view, the invention consists in the novel construction, combination, and arrangement of elements hereinafter described and claimed.

30 In the drawings, Figure 1 is a view of the device in side elevation, Figure 2 is an elevation from another angle, Figure 3 is a detail in section of the screen and the mounting means therefor, Figure 4 is a detail in 35 section showing the mounting of the spring for the yielding movement of the rotatable element, Figure 5 shows a portion of the rotatable element in side elevation, and Figure 6 is an elevation of a form of the device in 40 which teeth are provided only on one side of the rotatable element.

In carrying out my invention, I employ an upper frame 10 mounted on a suitable support or supports, such as legs 12. Extending upwardly from the frame 10 are vertical elements 14 supporting a box-like receptacle 15 for receiving the beans to be shelled.

This receptacle 15 is provided with openings 16 having communication with hoppers 18, whereby the material is brought into

position to be acted upon by the shelling devices per se.

A rotary disk 20 is provided with radial series of teeth or projecting elements 21, on both sides thereof, these teeth cooperating with teeth 22 on the stationary disks 23. The stationary disks are suitably supported, as by means of brackets 24 connected with frame 10. It will be understood that the respective series of teeth of the stationary elements and the rotary element are so spaced that the teeth on latter pass between those on the former.

The rotary disk 20 is supported on a shaft 25 having its bearings at 26 and 27 in the stationary disks, and the shaft carries on one end a crank element 28 connected by pitman 29 with a screen 30. This screen is mounted for movement about its central longitudinal axis, pins 31 and 32 connected with the end members of the screen being received by bearings 31' and 32' supported by the frame. The screen is inclined as shown, and the beans pass to a receptacle beneath the frame 10, the waste material passing off from the lower end of the screen.

A fly wheel 40 is mounted on shaft 25 and also a pulley 41 driving a belt 42 passing over pulley 43 on shaft 44 of the rotary 80 fan 45, the latter serving an obvious purpose in the operation of the device.

In the drawings, I have also shown a single acting machine, in which the rotary disk 20' is provided with teeth on one side 85 only, for cooperation with the teeth of the stationary disk 23'. Shaft 25' carries the rotating disk.

In order to make it possible to use the device for shelling beans of different sizes, I provide for the yielding of the rotary disk, so that beans or peas of large size may be shelled without being damaged by the teeth. This yielding movement is made possible by the use of a spring 36, mounted as shown.

95 What I claim is—

In a device of the class described, a rotatable element having teeth formed on the surfaces thereof, a stationary element spaced from the rotatable element and being disposed in a plane parallel therewith, said stationary element having teeth cooperating

with those first named, resilient means for controlling the cooperation of the toothed elements, a hopper for feeding material toward the rotatable element, a second stationary element having teeth thereon, and located on the side of the rotary element opposite to the stationary element first named, and a second hopper for feeding material be-

tween the rotary element and the second stationary element, the resilient means automatically adjusting the rotary element to a position determined by the relative size of graded material placed in the respective hoppers. 10

In testimony whereof I affix my signature.
MICHAEL MOLNAR.
